EMERY J. BARSONY, OF HAMTRAMCK, MICHIGAN, ASSIGNOR OF ONE-HALF TO MINNIE E. TRAPP, OF DETROIT, MICHIGAN

ELECTRICALLY-OPERATED DOOR CLOSING AND LOCKING MECHANISM

Application filed August 19, 1927. Serial No. 214,082.

This invention relates to certain new and useful improvements in electrically operated door closing and locking mechanisms and has for its primary object to provide a door closing and locking mechanism for bank buildings and similar houses with the operation of the doors controlled by a bank employee for the purpose of preventing the escape of a robber or highwayman with the door retained in locked condition and releasable only from a distant point, such as in a police station.

A further object of the invention is to provide electrically operated door closing and locking mechanism of the above type in which a signal visible to the bank employee is rendered operative during closing movement of the doors while an audible signal at a distant point, as a police station, is simultaneously rendered operative to indicate that a robbery is being committed, the doors being retained in locked condition until released by a person at the police station.

A further object of the invention is to provide door closing and locking mechanism with associated signal devices of the above type with an electric motor for moving and holding the doors in locked condition, the motor being of the reversible type and switch controlled to effect closing and permit opening movement of the doors.

A still further object of the invention is to provide electrically operated door closing and locking mechanism for the above purposes adapted for association with any type of doors, such as doors of the swinging or revolving type, the mechanism associated with the swinging doors effecting closing movement thereof and holding the same in closed condition, while the mechanism associated with the revolving type of door operates to hold the revolving door against movement.

With the above and other objects in view that will become apparent as the nature of the invention is better understood, the same consists in the novel form, combination and arrangement of parts hereinafter more fully described, shown in the accompanying drawings and claimed.

In the drawings, wherein like reference characters indicate corresponding parts throughout the several views,

Figure 1 is a fragmentary front elevational view of a bank building with hinged closure doors, a part of the basement or foundation being shown in section with the door operating mechanism shown in elevation;

Figure 2 is a fragmentary top plan view of a part of the door operating mechanism shown in Figure 1;

Figure 3 is a detail sectional view taken on line 3—3 of Figure 2 showing the interlocking guide connection between a sliding contact block enclosing case;

Figure 4 is a detail sectional view taken on line 4—4 of Figure 2 showing one of the door operating sliding blocks;

Figure 5 is a fragmentary side elevational view of a part of the base supporting structure for one of the hinged doors;

Figure 6 is a detail sectional view taken on line 6—6 of Figure 5;

Figure 7 is a detail sectional view taken on line 7—7 of Figure 5 showing the ball bearing support for the hinged door; and

Figure 8 is a diagrammatic view of the wiring arrangement and electric motor for moving the hinged doors to closed position.

In the form of the invention shown in Figures 1 to 8, the electrically operated door closing and locking mechanism is illustrated as associated with doors of the horizontally swinging type, the reference numeral 1 designating the bank building in which the door opening 2 is closed by the hinged doors 3. The object of this invention is to provide devices for closing the doors if the latter are in open position and also for holding the doors against opening movement to prevent the escape of a person in the bank building 1, the door operating mechanism being disposed beneath the floor and controlled in its operation by one or more conveniently positioned push button switches, the electric devices also flashing a signal to the bank employee that the doors are properly operating and moving to locked position while a signal is also given at a distant point, such as at a police station.

The lower corner hinge or pivotal support for each of the swinging doors 3 forms a part of the door operating mechanism and as shown in Figures 1, 5 and 6, there is provided a two-part bracket support in which the upper part 4 in the form of an angle iron is provided with angle strap extensions 5 that are embedded in the foundation wall 6 extending between the base floor 7 and the bank floor 8. The lower part 9 of the two part bracket is of angle iron construction and is secured to the wall 6 by anchoring bolts 10 passing through the wall and retained by the base plate 11. Spaced disk plates 12 and 13 are carried by the parts 4 and 9 of the bracket and have interengaging portions 14 to prevent relative movement and also to hold the disk plates in spaced relation. The pivot bearing 15 for the lower corner edge of each door 3 comprises a bolt 16 with a U-socket 17 at its upper end for supporting the lower edge to the door, the bolt 16 being rotatable through the bank floor, 8, while the under side of the bearing 17 is provided with a circular race of bearing balls 18 in a corresponding race in the disk plate 19 for the absorption of the end thrust of the bolt. The lower end of the bolt 16 extends through the disk plates 12 and 13 and is retained in position by the cap nut 20. Each bolt 16 has an arm 21 fixed thereto between the disk plates 12 and 13 with bearing balls 22 interposed between the arm 21 and disk plate.

The operating means for the arms 21 comprise electrically operated devices that are mounted upon the tiers 23 between the walls 6, said devices comprising a box-like structure or casing 24 supported upon the tiers 23, open at its upper side and divided into two compartments 25 by the central partition 26. A block 27 is slidably mounted in each compartment 25 and is interlockingly engaged with the walls of the compartment by the tongue and groove connections 28. A lever 29 is associated with each sliding block 27, the lever being pivoted as at 30 upon the upper side of the casing 24 with a pin and slot connection 31 between one end thereof and a sliding block while the other end of each lever 29 has a pin and slot connection 32 with an adjacent arm 21. The slot 32 has an offset portion 33 at each end to receive the associated pin when the lever 29 moves to its limit in opposite directions to prevent end vibrations of the doors 3.

A longitudinal shaft 34 is journaled at its ends and also intermediate its ends in the casing 24 with the portions thereof extending through the compartment 25 being reversely threaded as at 35. A block 36 is slidably mounted in each compartment 25 outwardly of the sliding block 27 and has a tongue and groove connection 37 with the walls of the compartment, each block 36 having a threaded opening therein through

which the threaded portion 35 of the shaft 34 extends. When the blocks 36 are positioned at the outer ends of the compartments 25 as shown in Figure 2, the doors 3 are free to operate, each block 27 having an opening 38 therein for the free passage of the threaded portions of the shaft 34.

The shaft 34 is electrically operated for moving the blocks 36 toward the central cross partition 26 to hold the sliding blocks 27 against movement and when the blocks 36 are so disposed, the doors 3 are retained in their closed position. An appropriate wiring arrangement and operating means for the shaft 34 is shown in Figure 8, one end of the shaft 34 projecting from the casing 24 and having a beveled gear 39 fixed thereto that meshes with bevel gear 40 upon the shaft 41 that extends from the speed reducing gearing 42. The shaft 43 of the motor 44 communicates with the speed reducing gearing 42 and when the motor circuit is closed, the shaft 34 is operated for shifting the blocks 36, the motor 44 being of the reversing type for causing a reverse rotation of the shaft 34 and sliding movement of the blocks 36 in opposite directions in the compartment 25 of the casing 24. The wiring arrangement includes line wires *a* and *b*, the line wire *a* extending to the switch *d* which

may be of the push button type that is located in the bank building, the wire *e* from the push button switch *d* extending to the switch *f* at a distant point, such as a police headquarters. The wire *g* that is associated with the push button *d* extends to the transformer section *h* and continues therefrom at *i* to the contact *j* on the casing 24 that is supported by the insulating block *k*. The wire *m* from the transformer *h* extends to the bell *n* that is located in the police headquarters.

A second contact *o* carried by the insulating block *k* is connected by the wire *p* to the lamp *q* located in the bank, the wire *r* continuing from the lamp to the terminal 45 of the motor 44 and continuing from the motor as at *s* to the line wire *b*. Spaced contacts *j* and *o* are connected by the bridge piece *t* on the sliding block 36 and completes the circuit. It will therefore be understood that the bell at police headquarters rings while the lamp *q* in the bank is illuminated, and the motor 44 is being operated in the desired direction for shifting the blocks 36 toward each other and holding the blocks 27 that are connected to the doors 3 against movement. During this movement, the bridge piece *t* is displaced from the contacts *j* and *o* to break the circuit, the momentum of the motor shaft 43 insuring full movement of the blocks 36.

The push button *f* in police headquarters connects the wire *e* to the wire *u* that extends to the contact *v* upon the insulation block *w*, the contact *x* upon the insulation block *w* being connected to the contact *v* by the bridge

piece *t* upon the other sliding block 36 that has been moved into contact therewith. The wire *y* from the contact *x* leads to the terminal 46 of the motor 44 while the wire *v* extends from the terminal 46 to the return wire *s* that communicates with the line wire *b*. It will therefore be understood that when the push button *f* in the police headquarters is operated the motor 44 is driven in a reverse direction to retract the sliding blocks 36 to the outer ends of the compartment 25 and permit free sliding movement of the blocks 27 that are connected to the doors 3. When the doors 3 are to be normally retained in the closed position, but unlocked, the spring device is associated with the levers 29 for normally retaining the sliding blocks 27 in engagement with the intermediate partition 26, the spring 47 being anchored at its ends to the pins 31 as clearly shown in Figure 2.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a device of the kind described, a door pivoted for horizontal swinging movement, a sliding block operated by said door and movable in unison with said door slidably mounted stop block, engageable with said first named block for holding the same against movement and thereby locking said door, mechanical means for moving said stop block into and out of engaging position, a reversible motor operatively connected to said mechanical means, a circuit for said motor, a circuit closer adjacent said door for closing the circuit in one direction through the motor to lock the door, and a second circuit closer remote from the door for closing the circuit in the opposite direction through said motor to unlock the door.

2. In a device of the kind described, a door having movement between open and closed positions, a fixed guide member, a sliding block movable in said guide member, an operative connection between said block and door to move the block in one direction upon opening of the door and in the opposite direction upon closing of the door, a stop movable into and out of the path of the sliding block, and means to move said stop block into said path with the door closed and thereby prevent opening of said door.

3. In a device of the kind described, a door having movement between open and closed

positions, a fixed guide member, a sliding block movable in said guide member, an operative connection between said block and door to move the block in one direction upon opening of the door and in the opposite direction upon closing of the door, a stop movable into and out of the path of the sliding block, a screw rotatably supported by said guide and having thread engagement with said stop, and means to rotate said screw in one direction and the other to cause the stop to engage and disengage said block.

4. In a device of the kind described, a door having movement between open and closed positions, a fixed guide member, a sliding block movable in said guide member, an operative connection between said block and door to move the block in one direction upon opening of the door and in the opposite direction upon closing of the door, a stop movable into and out of the path of the sliding block, a screw rotatably supported by said guide and having thread engagement with said stop, an electric motor having operative connection with said screw, a circuit breaker actuated by the movement of said stop, and a circuit closer connected in series with said motor and circuit breaker.

5. In a device of the kind described, a door having movement between open and closed positions, a fixed guide member, a sliding block movable in said guide member, an arm carried by the door and projecting radially from the pivotal axis thereof, a lever pivoted intermediate its ends and having pin and slot connections with said block and arm, a stop movable into and out of the path of the sliding block, and means to move said stop block into said path with the door closed and thereby prevent opening of said door.

6. In a device of the kind described, a door having movement between open and closed positions, a fixed guide member, a sliding block movable in said guide member, an arm carried by the door and projecting radially from the pivotal axis thereof, a lever pivoted intermediate its ends and having pin and slot connections with said block and arm, a stop movable into and out of the path of the sliding block, a screw rotatably supported by said guide and having thread engagement with said stop, and means to rotate said screw in one direction and the other to cause the stop to engage and disengage said block.

7. In a device of the kind described, a door having movement between open and closed positions, a fixed guide member, a sliding block movable in said guide member, an arm carried by the door and projecting radially from the pivotal axis thereof, a lever pivoted intermediate its ends and having pin and slot connections with said block and arm, a stop movable into and out of the path of the sliding block, a screw rotatably supported by said guide and having thread engagement

with said stop, an electric motor having operative connection with said screw, a circuit breaker actuated by the movement of said stop, and a circuit closer connected in series with said motor and circuit breaker.

5. 8. In a device of the kind described, a pair of door leaves pivoted for opening and closing a door-way, a fixed guide member, a pair of sliding blocks movable in said guide member, arms each carried by a respective leaf and projecting radially from the pivotal axis thereof, levers each pivoted to the guide and having their ends provided with pin and slot connections to respective blocks and arms, 10 stops also slidable in said guide toward and from said blocks, a right and left hand screw screwed through said blocks, a reversible electric motor having operative connection with said screw, independent circuit breakers in series reversely with said motor and each actuated by the movement of a respective stop, one of said circuit breakers being open when the other is closed, and circuit closers each connected in series with a respective circuit breaker and the motor.

15. 9. In a bank and store protective mechanism, doors controlling entrance to the structure, a sliding block operatively engaged with each door to be moved upon opening and closing movement of the door, a sliding stop member for each block, means for moving the stop members relative to the blocks, an electric motor in communication with said means, control means adjacent the motor for moving the stop members into engagement with the blocks for holding the doors closed and remote operating means for moving the stop members away from the blocks to permit opening movement of the doors.

20. 10. In a bank and store protective mechanism, doors controlling entrance to the structure, a sliding block operatively engaged with each door to be moved upon opening and closing movement of the door, a sliding stop member for each block, means for moving the stop members relative to the blocks, an electric motor in communication with said means, control means adjacent the motor for moving the stop members into engagement with the blocks for holding the doors closed and remote operating means for moving the stop members away from the blocks to permit opening movement of the doors, the connections between the door and block including pivoted links, one attached to the door and the other pivoted intermediate its ends and pivoted to the blocks.

25. 11. In a bank and store protective mechanism, doors controlling entrance to the structure, a sliding block operatively engaged with each door to be moved upon opening and closing movement of the door, a sliding stop member for each block, means for moving the stop members relative to the blocks, an electric motor in communication with

said means, control means adjacent the motor for moving the stop members into engagement with the blocks for holding the doors closed and remote operating means for moving the stop members away from the blocks to permit opening movement of the doors, the connections between the door and block including pivoted links, one attached to the door and the other pivoted intermediate its ends and pivoted to the blocks, and a pin and slot connection between the pivotally connected links fashioned to hold the links against movement when moved to extreme positions in opposite directions.

30. 12. In a bank and store protective mechanism, doors controlling entrance to the structure, a sliding block operatively engaged with each door to be moved upon opening and closing movement of the door, a sliding stop member for each block, means for moving the stop members relative to the blocks, an electric motor in communication with said means, control means adjacent the motor for moving the stop members into engagement with the blocks for holding the doors closed and remote operating means for moving the stop members away from the blocks to permit opening movement of the doors, the stop member moving means including a screw reversely threaded at opposite ends and said stop members being threaded thereon.

35. 13. In a bank and store protective mechanism, doors controlling entrance to the structure, a sliding block operatively engaged with each door to be moved upon opening and closing movement of the door, a sliding stop member for each block, means for moving the stop members relative to the blocks, an electric motor in communication with said means, control means adjacent the motor for moving the stop members into engagement with the blocks for holding the doors closed and remote operating means for moving the stop members away from the blocks to permit opening movement of the doors, the stop member moving means including a screw reversely threaded at opposite ends and said stop members being threaded thereon, and the blocks having openings therein through which the screw freely extends.

40. 14. In a bank and store protective mechanism, doors controlling entrance to the structure, a sliding block operatively engaged with each door to be moved upon opening and closing movement of the door, a sliding stop member for each block, means for moving the stop members relative to the blocks, an electric motor in communication with said means, control means adjacent the motor for moving the stop members into engagement with the blocks for holding the doors closed and remote operating means for moving the stop members away from the blocks to permit opening movement of the doors, the stop member moving means includ-

ing a screw reversely threaded at opposite ends and said stop members being threaded thereon, a casing in which the block and stop members are slidably mounted with the screw journaled in the casing, and a slide guide connection between the blocks, stop members and casing.

15. In a bank and store protective mechanism, doors controlling entrance to the structure, a sliding block operatively engaged with each door to be moved upon opening and closing movement of the door, a sliding stop member for each block, means for moving the stop members relative to the blocks, an electric motor in communication with said means, control means adjacent the motor for moving the stop members into engagement with the blocks for holding the doors closed and remote operating means for moving the stop 20 members away from the blocks to permit opening movement of the doors, the stop member moving means including a screw reversely threaded at opposite ends and said stop members being threaded thereon, and 25 the blocks having openings therein through which the screw freely extends, a casing in which the block and stop members are slidably mounted with the screw journaled in the casing, and a slide guide connection between the blocks, stop members and casing.

30 In testimony whereof I affix my signature.
EMERY J. BARSONY.
